UNITED STATES PATENT OFFICE

MARCEL PIERRE DARAGON, OF LYON, FRANCE

DEMOUNTABLE GYMNASTIC APPARATUS

Application filed May 10, 1928, Serial No. 276,731, and in France May 18, 1927.

The present invention has for its object a demountable gymnastic apparatus, the different elements of which are combined in such a way that it forms an absolutely complete and non-cumbersome apparatus suitable for giving lessons in physical culture and allowing of practicing all exercises such as 5 escalading, climbing, trapeze and fixed bar work, ring work, balance suspension, lateral 10 translation jumping, Swedish bar exercises etc.

The apparatus can be set up almost instantaneously, by means of four guy-ropes or it may be fixed to remain on the ground. It is 15 adjustable as to the height of the members with respect to the ground so as to allow its adaptation to persons of all ages. It can, further, in the case of very small places, be set up only in part.

20 It is essentially constituted of two vertical uprights surmounted by a horizontal platform of open work and on each of the sides of which is a horizontal ladder supported by one of the central uprights and by an auxiliary support.

25 All this structure which is demountable and can be set up very rapidly on any ground is provided also with ropes, poles, rings, a fixed bar and Swedish bars.

30 The invention can be well understood with the aid of the following description and the annexed drawing, which description and drawing are it is understood, given by way of example.

35 Fig. 1 is a view of the whole, in perspective.

Fig. 2 shows on a larger scale, the detail of the method of fixing the fixed bar.

40 Figs. 3 and 4 are two detail views in elevation respectively from the side and from the front, showing the method of assemblage of the upper platform with the uprights of the structure.

45 Two vertical uprights *a* and *b* constituted by ladders have at their upper part a horizontal open-work platform *c* which serves as a support for a small movable ladder *d* terminated with handles *e* and for two bars *f* also smooth ropes *g*, poles *h* and finally rings *i*.

The two vertical uprights *a* and *b* serve 50 also as support for a fixed bar *j* the height

of which can be regulated with respect to the ground.

The latter have also, in their lower part, each two parallel slides, *k* and *l* in which can be displaced in the direction of the height 55 a ladder *m* and two Swedish bars *n* which are supported at their ends by a support *o* which may be constituted by a foot ladder also comprising two slides *p* and *q*.

Holes *r* formed in these slides and receiving pins *s* allow of modifying the height of 60 the bars *n* and of the ladder *m*.

Finally the system of the movable assemblage of the platform *c* and of the vertical uprights *a* and *b* is constituted (Figs. 3 and 4) 65 by forks *t* terminating each of the said uprights and in which pins *u* engage, the extreme cross-members *v* of the said platform which are integral with arms *w* resting on the upper strengthened rungs *x* of the ladders 70 *a* and *b*.

On each of the latter a flat iron member *y* fixed to rungs *x* by stirrups *2* (Fig. 2) serves as a support for the fixed bar *j* of which the height with respect to the ground can be 75 regulated by utilizing one or other of the supports *3*.

The two vertical uprights *a* and *b* which carry a plumb line, are maintained in the vertical position by stays *4* fixed to the 80 ground.

In the case where the apparatus is erected to remain in a place then the uprights may be fixtures.

By the invention an apparatus is provided 85 which besides its features of rapid mounting and demounting allows of effecting all gymnastic exercises.

The invention is not limited to the sole method of construction described but comprises all modifications of construction and particularly its realization as a demountable 90 toy.

Having now particularly described and ascertained the nature of my said invention 95 and in what manner the same is to be performed, I declare that what I claim is:

1. Demountable gymnastic apparatus comprising a pair of upright supporting ladders, an open frame connecting and detach- 100

5 ably secured to the upper ends of said ladders, a pair of supporting ladders in line with and spaced from the outer sides of the first named ladders, Swedish bars having their outer ends detachably secured to the second named ladders and supporting means for the inner ends of the Swedish bars, said supporting means being detachably and adjustably secured to the first named ladders.

10 2. Apparatus as claimed in claim 1, in which the open-work platform comprises longitudinal bars which bear on the uppermost bars of the first named ladders and cross bars on said longitudinal bars and said first named ladders are provided at their upper ends with means to detachably secure the ends of the cross bars of said platform to the upper ends of said ladders.

15 3. Apparatus as claimed in claim 1, including supports detachably and adjustably secured to the first named ladders and a bar detachably secured at its ends to said supports and arranged between and serving to brace the first named ladders.

20 25 3. In witness whereof I affix my signature.
MARCEL PIERRE DARAGON.
